UNITED STATES PATENT OFFICE.

SIMON O. ROSENFELD, OF WEST POINT, MISSISSIPPI.

DRINKING-CUP.

991,246.

Specification of Letters Patent.

Patented May 2, 1911.

Application filed June 3, 1910. Serial No. 564,851.

To all whom it may concern:

Be it known that I, SIMON O. ROSENFELD, a citizen of the United States, residing at West Point, in the county of Clay and State 5 of Mississippi, have invented new and useful Improvements in Drinking-Cups, of which the following is a specification.

This invention relates to a drinking cup folded from paper so that it will be flexible 10 enough to fold flat for convenience in carrying the cup in the pocket.

The invention has for one of its objects to improve and simplify the construction of cups of this character so as to be comparatively easy and inexpensive to manufacture, and so designed that it will be comparatively rigid when opened out and filled 15 with water.

Another object of the invention is to im- 20 prove a cup of that type made from a single piece of paper and crimped into receptacle form, the improvements consisting of a reinforcing cord extending around the brim of the cup and outwardly and downwardly 25 folded tabs or ears which are glued to the crimped body of the cup to assist in stiffening and reinforcing the body and at the same time hold the cord in place, and, furthermore, the said ears cover the folds or crimps 30 in the body of the cup so that there will be no danger of tasting glue which might ooze out of the crimps in the manufacture of the cup.

With these objects in view and others, as 35 will appear as the description proceeds, the invention comprises the various novel features of construction and arrangement of parts which will be more fully described hereinafter and particularly set forth in 40 the claim appended hereto.

In the accompanying drawing, which illustrates one embodiment of the invention, Figure 1 is a perspective view of the cup with a portion of the brim broken away. Fig. 2 is a section taken horizontally 45 through the body of the cup. Fig. 3 is a plan view of the paper or fiber blank from which the cup is formed.

Similar reference characters are employed 50 to designate corresponding parts throughout the views.

The cup is preferably made of a blank formed of a single piece of paper or other fibrous material, as shown in Fig. 3, the 55 said blank consisting of a circular or dish-

shaped piece 1 which has a radius equal to one half the bottom of the cup plus the height of the body thereof. This piece of paper 1 has outwardly-extending ears or tabs 2 which are disposed slightly obliquely 60 to a radial line passing through each tab. The portion inclosed within the dotted circle 3, forms the bottom 4 of the cup, while the portion between the said dotted circle and the periphery of the blank constitutes 65 the body of the cup, the said dotted circle representing the line on which the body is bent or crimped into shape. This body portion 5 is shaped into a flaring or frustoconical form by any suitable die, and during 70 this shaping, crimps or folds will be made on the lines 6 and 7, the lines 7 being continuations of the edges of the tabs or ears 2, while the lines 6 are disposed between each pair of converging lines 7 and pass between adjacent ears 2, the point of meeting between the lines 6 and 7 being adjacent the periphery of the bottom 4. When the cup is formed from a blank in this manner, as shown in Fig. 1, the crimps will be disposed 75 slightly out of a vertical line, because the lines are disposed obliquely to radii of the blank, and the ears 2 will fold outwardly and downwardly so that the tabs will cover the crimps at the brim of the cup. In folding the blank, the portions thereof disposed between adjacent converging lines 7 will be 80 covered with mucilage and folded into the cup so that the portions between the lines 6 and 7 will adhere to each other and thus 85 form a grip extending the full height of the body of the cup and thereby materially stiffen the same. Any mucilage that might ooze out from the crimp on to the outer surface of the body will be covered by the ears 90 2 which cover the cracks at the crimps. Before the ears 2 are folded down, a reinforcing band such as a cord 8 is applied to the brim of the cup at the outside thereof to 95 prevent tearing, and this band is held in place by the tabs being glued to the outer surface of the cup body. A cup constructed in this manner is extremely serviceable and, while it can be folded into a small space for carrying in the pocket, it nevertheless is 100 105 strong and durable.

Having thus described the invention, what I claim as new, is:

A paper cup comprising a circular bottom, an upwardly flared body, said body 110

having folds or creases disposed obliquely to a vertical line, ears integral with the brim of the body and disposed between the folds, said ears being folded outwardly and down-
5 wardly and glued to the outer surface of the body and extending obliquely to the vertical to cover the edges of the folds of the body, and a cord extending continuously around the body and concealed and held in place

under the downwardly folded ears to 10 strengthen the brim of the cup.

In testimony whereof I affix my signature in presence of two witnesses.

SIMON O. ROSENFELD.
